United States Patent [19]
Dickhadt

[11] **Patent Number: Des. 282,968**
[45] **Date of Patent: ** Mar. 11, 1986**

[54] **TRANSCUTANEOUS ELECTRICAL NERVE STIMULATOR OR SIMILAR ARTICLE**

[75] Inventor: **Eugene A. Dickhadt**, New Brighton, Minn.

[73] Assignee: **Medtronic, Inc.**, Minneapolis, Minn.

[**] Term: **14 Years**

[21] Appl. No.: **510,021**

[22] Filed: **Jul. 1, 1983**

[52] U.S. Cl. **D24/41; D24/36**

[58] Field of Search **D24/34, 36, 40, 41, D24/42; 128/419, 421, 422, 423**

[57] **CLAIM**

The ornamental design for transcutaneous electrical nerve stimulator or similar article, as shown and described.

DESCRIPTION

FIG. 1 is a top front isometric view of a transcutaneous electrical nerve stimulator or similar article, showing my new design;

FIG. 2 is a bottom rear isometric view thereof;

FIG. 3 is a top front isometric view of the device open;
FIG. 4 is a bottom rear isometric view of the device open.

Fig. 1**Fig. 2****Fig. 3****Fig. 4**
